UNITED STATES PATENT OFFICE

144,422

DESIGN FOR A RACK FOR TROUSERS AND OTHER ARTICLES

Allan P. Sempers, Venice, Calif.

Application August 21, 1945, Serial No. 121,534

Term of patent 14 years

(Cl. D33—8)

To all whom it may concern:

Be it known that I, Allan P. Sempers, a citizen of the United States of America, residing in the city of Venice, in the county of Los Angeles, State of California, have invented a new, original, and ornamental Design for a Rack for Trousers and Other Articles, of which the following is a specification, reference being had to the accompanying drawing, forming a part thereof.

for trousers and other articles, showing my new design;

I claim:

The ornamental design for a rack for trousers and other articles, substantially as shown.

ALLAN P. SEMPERS.
